UNITED STATES PATENT OFFICE.

JAMES M. WAGNER, OF CHICAGO, ILLINOIS, ASSIGNOR, BY DIRECT AND MESNE ASSIGNMENTS, TO WILLIAM L. MCKAY, OF CHICAGO, ILLINOIS.

TELEPHONE-RECEIVER APPLIANCE.

1,321,265.

Specification of Letters Patent. Patented Nov. 11, 1919.

Application filed August 14, 1916. Serial No. 114,781.

To all whom it may concern:

Be it known that I, JAMES M. WAGNER, a citizen of the United States, residing at Chicago, in the county of Cook and State of Illinois, have invented new and useful Improvements in Telephone-Receiver Appliances, of which the following is a specification.

This invention relates to devices designed for application to telephone receivers and having for its object to improve the hearing and to exclude extraneous noises from the ears.

The present invention is an improvement in a similar device which is the subject matter of an application for Letters Patent filed May 27, 1916, Serial No. 100346, and it consists in a novel combination and arrangement of parts to be hereinafter described and claimed.

In order that the invention may be better understood, reference is had to the accompanying drawing forming a part of this specification.

25 In the drawing,

Figure 1 is a perspective view of the device showing the manner in which it is used, and

Fig. 2 is a cross section thereof.

30 Referring specifically to the drawing, 5 denotes a sound-receiving member which is constructed so that it may be attached to the telephone receiver 6. The member 5 is a circular block of any suitable material, having a central cavity 7 on one side over which the ear end of the receiver 6 is placed. From the cavity 7 extend two ducts 8 which open through the edge or side of the member 5. These ducts are diametrically opposite and they extend from the cavity in opposite directions.

To the end of each duct 8, where it opens through the side of the member 5, is fitted a short rubber or other flexible tube 9 carrying a metal or other rigid sound-conducting tube 10 having at its outer end an ear-piece 11 for insertion into the ear. The two tubes 10 are spaced laterally and their outer ends have inward bends to place the ear pieces in proper position for insertion into the ears.

Between the tubes 10 is located a bowed spring 12 secured at its ends to the respective tubes, and having a normal tendency to draw the two tubes together.

In use, the member 5 is held over the mouth or ear end of the receiver 6, one hand holding the receiver and also holding the member 5 thereon. It will be understood, of course, that the side of the member 5 having the cavity 7 will be placed against the receiver. This side of the member 5 has a raised portion 13 through which the cavity opens, and this raised portion 13 is inserted into the mouth of the receiver. The part 13 tapers outwardly so that it readily fits various makes of receivers and it also fits snugly so that no sounds escape from the cavity except through the ducts 9.

To apply the device to the ears the tubes 10 are spread sufficiently to allow the parts 70 11 to be inserted into the ears, the spring 12 holding the device in this position, so that the one hand of the user is left free to grasp the receiver and hold the member 5 thereagainst, and the other hand is left free to 75 make notes. The ear pieces exclude all extraneous noises from the ears, and the tubes 9 and 10 conduct the sound issuing from the receiver 6 to both ears. The sound issuing from the receiver enters the cavity 7 and 80 passes through the ducts 8 into the tubes 9, and then passes through the tubes 10 to the ear pieces 11. Because of better hearing, continuity of conversation is assured, and the device is therefore a valuable accessory 85 in noisy places, and it also makes a telephone available to persons with defective hearing.

The device is simple, and can be readily applied to any ordinary telephone receiver 90 without making any changes in the structure or the shape thereof.

I claim:—

A telephone receiver appliance comprising a sound-receiving member shaped on one 95 side to fit against the ear end of the receiver and having on said side a cavity adapted to communicate with the receiver mouth, and also provided with ducts leading in opposite directions from said cavity and 100 opening through the outside of the member at diametrically opposite points, said member being adapted to be held manually over the ear end of the receiver and being detachable therefrom, flexible tubes connected 105 to the ends of the ducts which open through the side of the member, rigid sound-conducting tubes connected to the outer ends of

the flexible tubes, ear pieces on the outer ends of the sound-conducting tubes, and a bowed spring connected at its ends to the rigid sound-conducting tubes and positioned 5 therebetween, said spring having a normal tendency to draw the sound-conducting

tubes together, whereby said tubes are held in operative position supported by the ears of the person when the sound-receiving member is disengaged from the receiver. 10

In testimony whereof I affix my signature.
JAMES M. WAGNER.
